UNITED STATES PATENT OFFICE

ROBERT ALLEN TANNER, OF BARBOURSVILLE, WEST VIRGINIA, ASSIGNOR TO THE AMERICAN VALVE & METER COMPANY, OF CINCINNATI, OHIO, A CORPORATION OF OHIO

WHEEL AND RAIL LUBRICATOR

Application filed March 6, 1928. Serial No. 259,503.

This invention relates to new and useful rails B, B and cross ties C. I have illustrated improvements in wheel and rail lubricators a curve in the tracks and have applied my for lubricating the wheels of rolling stock invention in cooperative relation to the and for curved rails of a railway track. curved rails whereby the outer curved rail Among the several objects of my invention of each track, as well as the wheel flanges of 50 are to provide a lubricating device for the the rolling stock, will be properly oiled. purpose described which is automatic in its Each rail includes the usual head 5, web 6 operation; is adaptable for either single or and base flange 7. My invention embodies an oil reservoir D double tracks; is simple in construction, and is therefore cheap to manufacture.

With these and other objects in view which will more fully appear, the nature of the invention will be more clearly understood by following the description, the appended claims, and the several views illustrated in the accompanying drawings.

In the accompanying drawings:

Fig. 1 is a plan view of a double track equipped with my invention,
20 Fig. 2 is a longitudinal sectional view thereof,

Fig. 3 is an enlarged cross section taken on the line 3—3 of Fig. 1,

Fig. 4 is a top plan view of Fig. 2, the rail being shown in section and the oil reservoir 25 in plan,

Fig. 5 is a perspective view of the actuating lever,

Fig. 6 is a sectional view of the packing gland,

Fig. 7 is a plan view showing the application of my invention to a single track,

Fig. 8 is a longitudinal sectional view,

Fig. 9 is a plan view showing my invention separate from the track,

Fig. 10 is an enlarged sectional view taken on the line 9—9 of Fig. 7.

Like reference numerals designate corresponding parts throughout the several figures of the drawings.

Referring to the accompanying drawings, and particularly to Figures 1 to 6 thereof in which I have shown my invention applied to a double track railway, A, A indicates the two tracks. Each track includes the usual

having a bottom 8, an outer side wall 9, an inner inclined side wall 10, end walls 11 and 12, a top 13, and one or more supporting brackets 14. The reservoir is supported on the ties and is located adjacent the inner face of the outer rail and below the head thereof.

The outer portion of the container, that is, that portion which is adjacent the rail, fits between the head 5 and base flange 7 and lies against the web 6 of the rail whereby a portion of the reservoir projects laterally from the rail. The top 13 is provided with an elongated opening 15 which parallels the rail and is located just beyond the head 5. An

Fig. 4 is a top plan view of Fig. 2, the rail being shown in section and the oil reservoir of a flat metal plate is normally located with 70 in the reservoir portion projecting upwardly through the opening 15 and in contact with the rail head 5. The upper edge of the plate is bevelled as at 17 for contact with the flange 18 of the wheel 19 of the rolling stock.

This distributing bar 16 is therefore normally disposed in contact with the rail head 5, and is adapted to be moved downwardly and entirely submerged within the oil of the reservoir. In this upper position the oil will be

transferred to the flange 18 of the wheel 19 of the rail stock by its engagement with the bevelled edge 17 of the bar, and the oil from the flange 18 will be thereafter transferred to the head of the outer rail around the curved portion of the tracks.

In order to support the distributing bar 16 whereby it may be moved up and down, I have provided a pair of horizontal pins 20, 20 which are rigidly secured to the outer wall 9 of

the reservoir. Supported by these pins 20, 20 is a spacer bar 21 which is located between the outer wall 9 of the reservoir and the distributing bar 16. The bar 16 is provided with a pair of cam slots 22, 22 through which the inner ends of the pins 20 project. These slots extend upwardly at an inclination to the vertical and the upper end of each slot terminates in a horizontal portion 23.

16 The distributing bar 16 is yieldably supported in its uppermost position as shown in Figs. 2 and 3. For this purpose the end wall 12 of the reservoir is provided with an opening in which is located a packing gland 24. 15 A rod 25 is slidable in said gland and the inner end thereof is pivotally connected as at 26 to one end of a link 27, the other end of the link being pivotally connected as at 28 to the distributing bar 16. A rod 29 extends parallel 20 with the rail and one end thereof is pivotally connected as at 30 to the other end of the sliding rod 25. This rod 29 slides through an opening formed in a bracket 31 which is fixed to one of the ties C. An adjustable collar 32 is secured to the rod 29 on the side of the bracket 31 opposite the pivot 30, and a coil spring 33 is disposed around the rod 29 between the bracket 31 and the collar 32. The spring 33 therefore serves to yieldably retain 25 the distributing bar 16 in its normal or uppermost position.

In order to automatically lower the distributing bar 16 into the oil and completely submerge the bar therein, I have provided an 35 actuating means operable by the passage of rolling stock along the rails. It is a well known fact that every rail has a certain amount of flexibility under the weight of 40 passing rolling stock, and I have employed this flexible rail as a means for actuating my lubricating device. To this end, I have positioned a tie X between a pair of ties C, C. This tie X has its upper surface 34 disposed below and in spaced relation to the base 45 flange 7 of the rail. Supported on this tie X is a bearing plate 35 in which the horizontal axis 36 of an actuating lever Y is journaled. This lever Y is provided with a crank arm 37 which extends under the associated rail, and 50 journaled on this crank arm is a roller 38 which is normally engaged under the base flange of said rail. The crank arm 37 is provided with a second arm 39 which extends upwardly and has its upper end pivotally 55 connected as at 40 to the adjacent end of the rod 29. As a result, when rolling stock passes over the rail C, the rail will flex and move downwardly thus rocking the crank arm 37 and correspondingly moving the lever 60 arm 39 in a direction towards the right, as viewed in Fig. 1. This movement of the lever 39 compresses the spring 33 and also exerts a horizontal thrust to the oil distributing bar 16. As a result of this thrust, the cam slots 65 22, 22 cooperating with the stationary pins

20, 20 will cause the distributing bar 16 to be moved downwardly to a point adjacent the bottom of the reservoir. Consequently the distributing bar 16 will be entirely submerged within the oil. If for any reason the rail should be flexed downwardly for an abnormal amount, injury to the distributing bar will be avoided by reasons of the upper ends 23, 23 of the cam shaped slots 22, 22 permitting additional lengthwise movement to the bar 16 70 but without forcing said bar to be moved downwardly into direct contact with the bottom of the reservoir. 75

Should any abnormal or downward flexing movement be imparted to the rail by the passage of rolling stock thereover, such action might sever the crank arm 37 from its journal 36. To avoid this possibility, I have supported the plate 35 on which the lever Y is fulcrumed upon a yieldable support. I have provided the tie X with a plurality of guide bolts 41, the upper ends thereof projecting above the tie X and passing through openings formed in the plate 35. Formed in the tie X and extending downwardly from the upper surface thereof around each bolt 41 is a seat 42. A coil spring 43 surrounds the bolt 41 and is located within the seat 42, the lower end bearing against the bottom of the seat 42 and the upper end bearing against the under face of the plate 35, thus yieldably holding the plate 35 above and in spaced relation to the tie X. This space between the plate 35 and the tie X is sufficient to allow maximum downward flex of the rail and consequently 700 the crank arm 37 will not be injured. Secured to the upper ends of each bolt 41 is a pair of lock nuts 44 by means of which the position of the plate 35 relative to the base flange 7 of the rail may be adjusted. 750

From an inspection of Fig. 1, it will be observed that my improved lubricating device is located at one end of the curved track portion and consequently when rolling stock passes over the rails, the downward flex of the rail due to the weight of the rolling stock will force the crank arm 37 downwardly through the medium of the roller 38 which is constantly engaged by the under face of the base flange 7. This movement will cause the distributing bar 16 to be moved downwardly against the tension of the spring 33 so as to fully submerge said bar within the oil. After the wheels of the rolling stock have passed over the rail directly above the crank arm 37, the spring 33 will cause the distributing bar 16 to be elevated whereby the upper portion thereof will be disposed in direct contact with the rail head 5. Consequently the oil film which is on the upper portion of the bar 16 will be first transferred to the wheel flange 18, and subsequently transferred by said flange 18 to the curved portion of the track. 850

In order to prevent the wheel flange from 900 abruptly engaging the approaching end of

the distributing bar and thereby injure the latter, I employ a guard rail 45 with the inner rail of the track and located at a point directly opposite the reservoir.

5 By providing a downwardly inclined inner wall 10 to the reservoir, I have provided means for utilizing practically all of the oil that is placed within the reservoir. The oil may be placed within the reservoir through the opening 15 or through any suitable opening not disclosed. The top 13 of the reservoir may be constructed in any suitable manner to meet the requirements of this invention.

When my invention is applied to a single track, such as is illustrated in Figs. 7 to 10, I locate the reservoir centrally of the curved portion of the track and locate the operating lever on the opposite side of the rail from the reservoir. This arrangement permits the oiling of the rail and wheel flanges in opposite directions from the reservoir due to the rolling stock going in opposite directions. In this form of my invention, the connecting rod 29 is pivotally connected at its outer end as at 46 to the upper end of an arm 47 of a U-shaped lever 48 which is fulcrumed at 49 upon a bracket 50 located between a pair of adjacent ties C, C. The other arm 51 of the lever 48 is pivotally connected as at 52 to a rod 53 which in turn is pivotally connected at its opposite end as at 54 to the upper end of the lever Y. The lever Y is in the present instance fulcrumed upon a yieldable support mounted upon a tie X which is located under the reservoir D. Consequently when rolling stock passes over this curved single track, the rail directly adjacent the reservoir D will flex downwardly and cause the lever Y to be swung to the right as viewed in Fig. 8. This movement of the lever Y will through the rod 53 pull the U-shaped lever 48 to the right against the tension of the spring 33 and thereby force the distributing bar 16 downwardly into the oil within the reservoir. After the rolling stock has left that portion of the rail, the spring 33 will immediately return the distributing bar 16 to its upper position in contact relation with the rail head.

It is of course to be understood that the details of structure and arrangements of parts may be variously changed and modified without departing from the spirit and scope of my invention.

55 I claim:

1. In a rail lubricating device, the combination of a flexible rail, of an oil reservoir located adjacent the rail and below the head thereof, an oil distributing bar within the reservoir and normally disposed in a position along side of the rail head, and means for moving the bar downwardly into the reservoir through the flexing of the rail by the weight of rolling stock passing along said flexible rail.

2. In a rail lubricating device, the combination of a flexible rail, of an oil reservoir located adjacent the rail and below the head thereof, an oil distributing bar within the reservoir and normally disposed in a position along side of the rail head, a lever engageable by the flexible rail through the weight of rolling stock passing along said rail, and means connected with the bar and lever for moving the bar downwardly into the reservoir upon movement of said lever.

3. In a rail lubricating device, the combination of a flexible rail, of an oil reservoir located adjacent the rail and below the head thereof, an oil distributing bar within the reservoir and normally disposed in a position along side of the rail head, a lever engageable by the flexible rail through the weight of rolling stock passing along said rail, means connected with the bar and lever for moving the bar downwardly into the reservoir upon movement of said lever, and means including a spring for automatically returning said bar and lever to their initial positions subsequent to the rolling stock passing over said flexible rail.

4. In a rail lubricating device, the combination with a flexible rail, of an oil reservoir located adjacent the rail and below the head thereof, and means for lubricating the rail including an operating lever fulcrumed upon a vertically yieldable support and operated through the flexing of the rail by the weight of rolling stock passing along said rail, and an oil distributing bar within the reservoir and movable into lubricating engagement with the rail upon movement of the operating lever.

5. In a rail lubricating device, the combination of a flexible rail, of an oil reservoir located adjacent the rail and below the head thereof, an oil distributing bar within the reservoir and normally disposed in a position along side of the rail head, means including a lever fulcrumed upon a vertically yieldable support for moving the bar downwardly into the reservoir through the flexing of the rail by the weight of rolling stock passing along said flexible rail, and means for adjusting the tension of said yieldable support.

6. In a rail lubricating device, the combination of a flexible rail, of an oil reservoir located adjacent the rail and below the head thereof, a pair of horizontal pins secured to and disposed within the reservoir, an oil distributing bar having cam slots for receiving said pins, and means including a lever operable by the flexing of the rail for moving the bar downwardly through the pin and slot connections.

7. In a rail lubricating device, the combination with a rail including a head, web, and flange, of an oil reservoir fitting under the head of the rail and projecting laterally be-

yond said head, a pair of horizontal pins secured to and disposed within the reservoir, an oil distributing bar located within the reservoir and having cam slots for receiving said pins, said bar being movable upwardly to a position in close parallel relation to the rail head, and means including a lever for moving the bar downwardly.

In testimony whereof, I have hereunto subscribed my name.

ROBERT ALLEN TANNER.
